UNITED STATES PATENT OFFICE.

CHARLES L. MERRY, OF KANSAS CITY, MISSOURI, ASSIGNOR TO MERRY OPTICAL COMPANY, OF KANSAS CITY, MISSOURI, A CORPORATION OF MISSOURI.

DESIGN FOR A LENS-EAR FOR SPECTACLE OR EYEGLASS MOUNTING.

48,907.

Specification for Design.

Patented Apr. 18, 1916.

Application filed January 4, 1915. Serial No. 528. Term of patent 7 years.

To all whom it may concern:

Be it known that I, CHARLES L. MERRY, a citizen of the United States, residing at Kansas City, in the county of Jackson and State of Missouri, have invented a new, original, and ornamental Design for a Lens-Ear for Spectacle or Eyeglass Mountings, of which the following is a specification, reference being had to the accompanying drawing, forming part thereof, wherein the

figure is a perspective view of a lens-ear for spectacle or eyeglass mountings, showing my new design.

I claim:—

The ornamental design for a lens ear for spectacle or eyeglass mounting as shown.

CHARLES L. MERRY.
